United States Patent Office

Des. 227,288
Patented June 12, 1973

227,288

LAWN TREATING MACHINE

Robert Picardat, 7712 Ridgecrest Drive,
Alexandria, Va. 22380

Filed May 6, 1971, Ser. No. 141,088

Term of patent 14 years

Int. Cl. D15—03

U.S. Cl. D40—1 E

FIG. 1.

FIG. 2.

FIG. 3.

FIG. 4.

FIG. 5.

FIG. 1 is a top plan view of the lawn treating machine;
FIG. 2 is a side elevation of the machine;

FIG. 3 is a side elevation of the machine, looking at
the side opposite FIG. 2;

FIG. 4 is a bottom plan view of the machine; and

FIG. 5 is a front elevation of the machine.

I claim:

The ornamental design for a lawn treating machine, as
shown.
